(57) **CLAIM**

The ornamental design for a “plant identification marker”, as shown and described.

DESCRIPTION

FIG. 1 is a front elevational view of a “plant identification marker” showing my new design, the rear elevational view being the same;

FIG. 2 is a left side elevational view thereof, the right side elevational view being the same;

FIG. 3 is a top plan view thereof;

FIG. 4 is a bottom plan view thereof; and,

FIG. 5 is a perspective view thereof.
